CLAIM

I claim the ornamental design for the ear bud housing, as shown and described.

DESCRIPTION

FIG. 1 is a front view of the ear bud housing showing my new design;

FIG. 2 is a bottom view of the ear bud housing;

FIG. 3 is a top view of the ear bud housing;

FIG. 4 is a right-side view of the ear bud housing;

FIG. 5 is a left-side view of the ear bud housing;

FIG. 6 is a back view of the ear bud housing; and,

The broken line depict environment that forms no part of the claimed design.
